(Model.)

S. & A. C. MARTIN.
TURBINE WATER WHEEL.

No. 600,735.

Patented Mar. 15, 1898.

FIG. 1.

UNITED STATES PATENT OFFICE.

SAMUEL MARTIN AND ARTHUR C. MARTIN, OF MUDDY CREEK FORKS,
PENNSYLVANIA.

TURBINE WATER-WHEEL.

SPECIFICATION forming part of Letters Patent No. 600,735, dated March 15, 1898.

Application filed April 10, 1897. Serial No. 631,542. (Model.)

To all whom it may concern:

Be it known that we, SAMUEL MARTIN and ARTHUR C. MARTIN, of Muddy Creek Forks, in the county of York and State of Pennsylvania, have invented a new and Improved Turbine Water-Wheel, of which the following is a full, clear, and exact description.

This invention is a turbine water-wheel of that class in which the water is introduced to 10 the apparatus at the upper side of a platform and caused to course through the apparatus and be discharged at the under side of the platform.

This specification is the disclosure of one 15 form of our invention, while the claims define the actual scope of the conception.

Reference is to be had to the accompanying drawings, forming a part of this specification, in which similar characters of reference indicate corresponding parts in all the figures.

Figure 1 is a section on the line 1 1 of Fig. 2. Fig. 2 is a partial horizontal section of the invention. Fig. 3 is a fragmentary perspective view of one of the blades of the turbine, 25 and Fig. 4 is a fragmentary section on the line 4 4 of Fig. 2.

The platform 5 runs out horizontally from the plate 7. Standing rigidly on the plate 7 are a series of tangential partitions 8, forming 30 sluices through which the water may pass to the wheel, which is hereinafter described. The partitions 8 are rigidly attached to a top plate 9. The parts 5, 7, 8, and 9 therefore compose a rigid structure inclosing the turbine wheel proper. The top plate 9 is extended 35 out at each partition 8 to form a cover 17 for the chutes produced by the partitions 8.

Let into the plate 7 is a flat ring 10, slideable on the plate 7 and carrying the gates 11, 40 one for each of the sluices formed by the partitions 8, and movable toward and from the sluices to regulate the amount of water thrown into the casing. The inner edge of each partition 8 has a wear-plate 12, against which the 45 gates 11 slide, and the inner face of each partition 8, at approximately the middle thereof, has a wear-plate 13, which plates are engaged by the forward points of the gates 11 as the gates are moved to closed positions. The 50 plates 12 and 13 are of soft metal, so that they will effectually serve to form water-tight con-

nections. Turning on the exterior surface of a bearing 14 in the top plate 9 is a circular frame 15, having downwardly-extending arms 16, (shown by dotted lines in Fig. 1,) attached 55 to the gates 11. By these means as the frame 15 is turned the gates 11 will be moved in unison to regulate the amount of water thrown into the turbine wheel.

Held rigidly beneath the platform 5 and by 60 means of a spider 6 is a bearing 18, whereon is stepped a rotary shaft 19, which extends upwardly through the bearing 14 and carries the hub or body portion 20 of the turbine wheel. This hub or body portion 20 has a 65 surface gradually curved inward and thence outward, so that as the water enters from above the platform 5 its course will be gradually changed to a downward and thence slightly lateral direction. Blades 21 are attached to 70 the hub or body of the wheel, and each blade consists in a metallic plate running throughout the height of the wheel and having the upper portion of its outer edge within the circumference of the upper flange of the hub or 75 body 20 of the wheel, such upper flange or head being larger than the lower flange or head. The lower portion of each blade is provided with an extension 22, which forms the bucket of the blade. The buckets of the 80 blades are located below the plate 7, while the upper portions of the blades are above the plate 7. The inner edge of each blade 21, or those edges which lie against the body 20 of the wheel, is curved to describe approximately one-half a circle. The upper portion of the blade is curved on a greater radius than the lower part, the curvature of the upper part of the blade extending from the upper head of the hub forwardly and downwardly to the lower end of the sluice or chute, so that no portion of the blade opposite the 90 sluice is on a vertical line, the water thus being received on the forwardly and downwardly curved upper portion of the blade. 95 The wheel carries an annular band 23, which encircles the lower portions of the vertical edges of the blades and has its lower edge rested on the upper edges of the extension 22. The upper edge of the band 23 is level with 100 the platform 5. This band serves to confine the water properly within the blades and to

direct the water down into the buckets formed by the extensions 22. The upper portion of each blade or that part which is above the platform 5 first receives the impact of the water and serves to carry the water down out of the way of the next sluice, so as not to break the water that enters through said next sluice and thus destroy the force of the water. As the water falls below the platform 5 and enters the bucket of the blade the force of the water is exerted on the blade, and the wheel is turned. The direction of the flow of the water is reversed as the water passes over the extension 22 of each blade. The projections 22 also serve to prevent the spread or dissipation of the water before the proper time, which time is the period of discharge. As heretofore stated, the upper portion of each blade is curved on a greater radius than the lower portion, the upper curved portion extending forward and downward to such a distance that all the water entering the sluice is received on the downward-curved portion of the blade, the point where the upper and lower curved portions of the blade join being below the chute-casing, so that no portion of the water entering the sluice is received on a vertical portion of the blade. Where the water is received on the vertical portion of the blade, the tendency is to force the water outward against the sides of the chute-casing and into the current of water issuing from the sluice next ahead, thus retarding the flow of the water. The special form of blade employed overcomes this difficulty, as the water is received on the upper curved portion of the blade and is forced downward, so that the water from one sluice cannot come into contact with the water from the next sluice and destroy its force. When in position on the hub, the upper part of the receiving portion of the blade preferably extends farther to the rear than the lower part of the discharge portion, thus giving a short and free discharge for the water.

Having thus described our invention, we claim as new and desire to secure by Letters Patent—

1. The combination with a casing having an inwardly-extending plate and a series of partitions on said plate forming sluices for fluid, of a wheel within the casing having a hub or body portion and blades secured at their inner edges to the face of the hub or body portion, the inner edge of each blade being curved, the curvature of the upper portion of each blade being on a greater radius than the lower portion and extending from the upper part of the hub forwardly and downwardly throughout the depth of the sluice-casing, so that no portion of the blade opposite the sluice is on a vertical line, the lower portion of each blade below the sluice-casing having a rearwardly-curved extension, substantially as described.

2. The combination with a casing having an inwardly-extending plate, a series of tan-

gential partitions on said plate forming sluices for fluid and a platform supporting the casing, of a wheel within the casing having a hub or body portion and a series of blades secured to the face of the hub or body portion, the inner edge of each blade being curved and engaging the face of the hub or body portion, the curvature of the upper portion of each blade being on a greater radius than the lower portion and extending from the upper part of the hub forwardly and downwardly to the lower part of the sluice-casing, the lower portion of each blade below the sluice-casing having a rearwardly-curved extension, and an annular band encircling the blades and having its lower edge resting on the upper edges of the said extension, the said band extending upward to the upper surface of the inwardly-extending plate, substantially as described.

3. The combination with a casing having an inwardly-extending plate, and a series of tangential partitions standing rigidly on said plate and forming sluices for fluid, of a wheel having a hub or body portion, and blades secured to the face of the hub or body portion, the inner edge of each blade being curved and engaging the face of the hub or body portion, the curvature of the upper portion of each blade extending from the upper part of the hub forwardly and downwardly to the lower part of the sluice-casing, the lower portion of each blade below the sluice-casing having a rearwardly-curved extension, and an annular band encircling the blades and having its lower edge resting on the upper edges of the said extensions, substantially as described.

4. The combination with a casing having an inwardly-extending plate, of a series of tangential partitions standing rigidly on said inwardly-extending plate and forming sluices for fluid, a top plate connected with the partitions and having extensions at each partition forming covers for the sluices, a flat ring slidable on the inwardly-extending plate of the casing, a series of gates carried by the ring and moved in a circular line to open and close the sluices, and a circular frame turning on the top plate and having downwardly-extending arms attached to the gates, whereby when the frame is turned, the gates will be moved in unison, substantially as described.

5. The combination of a casing having an inwardly-extended plate, a series of tangential partitions standing on said inwardly-extended plate and forming sluices for fluid, a top plate supported on the partitions and having portions forming the top of the sluices, a ring sliding in the inwardly-extending plate of the casing, a series of gates carried by the ring and moved in a circular line to open and close the sluices, and a frame turning on the top plate and connected to the gates to move the same in unison.

6. The combination with a casing having an inwardly-extending plate, of a series of

tangential partitions extending upward from said plate and forming fluid-slides, a top plate connected with the partitions, a ring arranged to slide on the inwardly-extending 5 plate of the casing, and gates carried by the ring and movable to close the sluices, each of said tangential partitions being provided with a wear-plate against which the respective gate slides and each partition also having a wear-plate adapted to be engaged by the forward point of the gate as the latter is moved to closed position, and means for moving the gates in unison, substantially as described.

15 7. A turbine wheel having a body portion or hub and blades having their inner edges

curved and secured to the face of the hub or body, the upper portion of each blade being curved on a greater radius than the lower part, the curvature of the upper part of the 20 blade extending from the upper head of the hub forwardly and downwardly entirely across the sluice or chute so that no portion of the blade opposite the sluice is on a vertical line, the lower portion of the blade below 25 the chute-casing having a rearwardly-curved extension, substantially as described.
